DRILL POINT GAUGE

Filed Feb. 20, 1946

UNITED STATES PATENT OFFICE

2,547,284

DRILL POINT GAUGE

Arthur G. Rabuck, Royalton, Pa.

Application February 20, 1946, Serial No. 649,016

1 Claim. (Cl. 33—201)

1 This invention relates to new and useful improvements and structural refinements in drill sharpening gauges, more particularly, to a gauge which may be easily and conveniently applied to the drill after the same has been sharpened, in order to determine if the cutting edges thereof have been uniformly ground to a proper angle and if the drill point is correctly centralized.

A further object of the invention is to provide a gauge which may be universally applied to various sizes of drills.

Another object of the invention is to provide a gauge in which the adjustment for various drill sizes may be easily and accurately effected.

An additional object of the invention is to provide a gauge which is of simple construction and which cannot easily become damaged.

With the above more important objects in view, and such other objects as may become apparent as this specification proceeds, the invention consists essentially of the arrangement and construction of parts as illustrated in the accompanying drawings, in which:

Figure 1 is a side elevation of the invention;

Figure 2 is a cross sectional view taken in the plane of the line 2—2 in Figure 1;

Figure 3 is a cross sectional view taken in the plane of the line 3—3 in Figure 1;

Figure 4 is a cross sectional view taken in the plane of the line 4—4 in Figure 1;

Figure 5 is a cross sectional view taken in the plane of the line 5—5 in Figure 1, and

Figure 6 is a cross sectional view taken in the plane of the line 6—6 in Figure 1.

Like characters of reference are used to designate like parts in the specification and throughout the several views.

Referring now to the accompanying drawings in detail, the invention consists of a straight edged blade 10, which may, if desired, be inscribed with the conventional graduated scale 11. A stop 12 is pressed onto one end of the blade 10 and a gauge plate 13 is longitudinally slidable edge to edge on the blade, as will be clearly apparent from the accompanying drawings.

The gauge plate 13 is of a substantially triangular configuration and a U-shaped stirrup designated generally by the reference character 14 is secured to the plate 13 by the rivets 15. The rivets 15 extend through the side arms 16 of the stirrup, these side arms in turn, straddling the blade 10, as is best illustrated in the accompanying Figures 2 and 3.

The stirrup itself may assume the form of a cylindrical bar formed with an open, transversely

extending slot to accommodate the blade as shown.

The end of the stirrup 14 is provided with a screw-threaded aperture 17 adapted to receive an adjusting screw 18, the head of which may be suitably knurled to facilitate adjustment. An inverted U-shaped friction block 19 is positioned between the arms 16 of the stirrup and the shank of the screw 18 presses against this block and urges the same against the edge of the blade 10. It will be apparent that by loosening the screw 18, the friction of the block 19 against the blade 10 will be relieved and the stirrup 14 together with the associated blade 13 may be slid longitudinally along the blade 10, as will be hereinafter more fully described.

A traveller plate 20 is slidable edge to edge upon the gauge plate 13, the plate 20 being provided with a pair of spaced fingers 21. These fingers 20 are provided with a pair of aligned apertures 22 and a screw-threaded rod 23 passes freely through the apertures and parallels the traveller plate 20, as is best illustrated in the accompanying Figure 4. A knurled adjusting nut 24 is positioned on the rod 23 between the fingers 21, and one end of the rod is formed with a forked extremity 25 which straddles and is pivotally connected to the gauge plate 13 by means of a rivet-like pin 26.

A further stirrup 27 is used for retaining the traveller plate 20 on the gauge plate 13, the construction of the stirrup 27 being identical to that already described in connection with the stirrup 14.

The edges 28 and 29 of the plates 13 and 20 respectively, are complementary to the cross sectional contour of the point of a drill 30, when the latter is positioned parallel with and adjacent to the edge 31 of the blade 10 and, therefore, the included angle between the inclined edge 29 of the traveller plate 20 and the inclined edge 28 of the gauge plate 13 is equal to the included angle between the inclined edge 28 of the gauge plate 13 and the edge 31 of the blade 10.

The gauge plate 13 is inscribed adjacent its edge 28 with a graduated scale 32 conforming to the sizes of drills. This scale is readable against a reference index 33 inscribed on the adjacent plate 20, as is best illustrated in the accompanying Figure 1.

Having thus described the construction of the invention, its method of operation will now be presented.

When the invention is placed in operation, the drill 30 is positioned parallel with and adjacent to the edge 31 of the blade 10, as has already been

set forth. The position of the plate 13 on the blade may be set in accordance with the length of the drill by adjusting the stirrup 14.

Thereupon, the stirrup 27 is loosened and by rotating the nut 24, the plate 20 will be adjusted with respect to the plate 13 to accommodate a given size of drill.

When this adjustment has been made, the plate 20 is locked in position by tightening the stirrup 27 and the accuracy of the angle to which the cutting edges of the drill have been ground and the central disposition of the drill point may be readily determined by comparing the same with the gauge surfaces 28 and 29.

While in the foregoing there has been shown and described the preferred embodiment of this invention it is to be understood that minor changes in the details of construction, combination and arrangement of parts may be resorted to without departing from the spirit and scope of the invention as claimed.

What I claim as my invention is:

A drill sharpening gauge comprising in combination, a straight edge blade inscribed with a graduated scale, a trapezoidal gauge plate slidably mounted on one edge of said blade, said gauge plate having an inclined edge and graduations adjacent the inclined edge, said inclined edge being disposed at an included obtuse angle with respect to said blade, a substantially U-shaped member carried by said gauge plate and slidably mounted on said blade, a friction block in said U-shaped member, an adjustable screw carried by said U-shaped member urging said block against one edge of said blade, a traveller plate slidably mounted on the inclined edge of said gauge plate, said traveller plate having a reference index for registering with the graduations on said gauge plate, a further U-shaped member carried by said gauge plate and slidably receiving said traveller plate, means mounted on said further U-shaped member for retaining said

traveller plate in a selected adjusted position relative to said further U-shaped member and on the inclined edge of said gauge plate, a pair of spaced parallel fingers projecting laterally from one end of said traveller plate, a screw threaded rod extending through said fingers, the axis of said rod being spaced parallel to the axis of said traveller plate, a pivot pin securing one end of said rod to said gauge plate, and means threaded on said rod and disposed between said fingers for adjustment of said rod relative to said fingers, said traveller plate having an edge intersecting the inclined edge of said gauge plate and disposed at an included obtuse angle with the inclined edge of the gauge plate, the included angle between the inclined edge of said traveller plate and inclined edge of said gauge plate being equal to the included angle between the inclined edge of said gauge plate and one edge of said blade.
